FOREIGN PATENT DOCUMENTS

FR 2821580 A1 9/2002

Primary Examiner — Philip S Hyder(74) *Attorney, Agent, or Firm* — Muncy, Geissler, Olds & Lowe, P.C.(57) **CLAIM**

I claim the ornamental design for a cutter, as shown and described.

DESCRIPTION

FIG. 1 is a top, front, right perspective view of a cutter showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 a top, front, left perspective view thereof; and,

FIG. 9 is an exploded perspective view of the cutter.

The broken lines depict portions of the cutter in which the design is embodied that are not considered part of the claimed design.

1 Claim, 7 Drawing Sheets(56)
